**CONCRETE SAWING MACHINE HAVING
STABILIZING WHEELS**

Ray Tucker, Kansas City, Mo., assignor to Robert G. Evans Company, Kansas City, Mo., a partnership

Filed Mar. 27, 1956, Ser. No. 574,223

6 Claims. (Cl. 262—20)

This invention relates to a machine for cutting concrete to make expansion grooves or for making repairs as in the construction and maintenance of concrete highways.

The principal object of the invention is to provide a machine of this character which is highly maneuverable but is exceptionally stable to assure accuracy of the cuts and to prolong the life of the cutting blade.

Other objects of the invention are to provide for feeding the blade into the work under power, and to quickly release the power when lifting the blade out of contact with the work, and to provide for accurate and straight-away movement of the machine under power even when the machine is moving over rough, sloped or crowned surfaces.

In accomplishing these and other objects of the invention as hereinafter pointed out, I have provided improved structure, the preferred form of which is illustrated in the accompanying drawings wherein:

Fig. 1 is a side elevational view of a concrete cutting machine constructed in accordance with the present invention and showing the machine in operation to cut an expansion groove in a concrete slab.

Fig. 2 is a plan view of the machine, parts of which are broken away and other parts shown in section, to better illustrate the construction.

Fig. 3 is a longitudinal section on the line 3—3 of Fig. 2, showing the cutting blade lifted out of the cut and the machine in transport position.

Fig. 4 is a rear end view of the machine with a part of the cowling broken away to better illustrate the parts covered thereby.

Fig. 5 is a horizontal section on the line 5—5 of Fig. 3, to better illustrate the relative mounting of the cutting blade, the main traction wheels, and the stabilizing wheels which cooperate with the traction wheels in eliminating side sway and for maintaining accuracy of the cut produced by the cutting blade.

Fig. 6 is a plan view of the friction drive unit.

Fig. 7 is a detailed perspective view of one of the side arms of the friction drive unit.

Fig. 8 is an enlarged section on the line 8—8 of Fig. 4.

Fig. 9 is a fragmentary section on the line 9—9 of Fig. 8.

Fig. 10 is an enlarged detailed view of the controls for the speed transformer and the friction drive unit, the movable parts of the controls being in position for effecting a forward movement of the machine.

Fig. 11 is a similar view but showing the controls moved to position for stopping forward movement of the machine.

Fig. 12 is a perspective view of the parts of the controls shown in disassembled spaced relation.

Fig. 13 is a fragmentary section on the line 13—13 of Fig. 1 showing the manner of mounting and securing the handle bars in adjusted position.

Fig. 14 is a cross section on the line 14—14 of Fig. 5.

2

Referring more in detail to the drawings: 1 designates a machine constructed in accordance with the present invention for producing cuts in concrete slabs to form expansion grooves or to cut out sections of concrete when making repairs. The machine includes a main frame 2 for carrying a cutting blade 3 and an engine 4 for supplying the power for rotating the blade and effecting forward movement of the machine.

The frame 2 comprises a substantially rectangular platform having side members 5 and 6 and front and rear end members 7 and 8 carrying a floor plate 9. The frame 2 is pivotally mounted substantially midway its length on traction wheels 10 and 11. The traction wheels are rotatably mounted on the ends of an axle 12 which extends transversely from one side of the frame to the other and has its ends journaled in bearings 13 and 14. The bearings 13 and 14 are carried in brackets 15 and 16 which are secured to the under side of the frame 2 at points spaced inwardly from the side members 5 and 6, as best shown in Figs. 4 and 5. The wheels 10 and 11 are retained on the outer ends of the axle 12 by collars 12' that are suitably pinned to the axle as shown in Fig. 14. The main frame 2 is thus adapted to tilt on the axis of the traction wheels 10 and 11 so that the forward end is lowered when the rear end is raised, as shown in Fig. 1, to carry the blade 3 into and out of contact with the work.

The blade 3 is carried on an arbor shaft 17 that extends transversely under the forward end of the frame 20 and has its ends journaled in bearings 18 and 19 carried by brackets 20 and 21 depending from the under side of the frame 2 and which are preferably attached to the forward ends of the side members 5 and 6. The arbor shaft has reduced ends 22 and 23 projecting outwardly from the sides of the bearings 18 and 19 to form shoulders 24 and to mount the cutting blade 3 on one or the other of the ends of the shaft, as desired. The cutting blade is in the form of a disk of standard design and diameter to produce a desired width and depth of cut. 35 Usually the blades are of three standard diameters, with a central opening of common diameter to pass over one or the other ends of the arbor shaft and to be clamped thereon between clamping plates or washers 25 and 26, the inner plates 25 being fixed to the arbor shaft and 40 backed by the shoulders 24 to seat the blade thereagainst for retention by an outer plate 26 when a nut 27 is turned onto a threaded terminal of the ends 22 and 23. To additionally secure the cutting blade, the outer clamping plates carry dowel pins 28 (Fig. 5) that 45 pass through a suitable opening in the blade and into registering openings in the inner plates 25, as shown in Figs. 2 and 5.

The engine 4 is mounted on the main frame at a point substantially above the traction wheels with the power shaft 29 thereof extending parallel with the arbor shaft and mounting a pulley 30 in registry with a pulley 31 fixed to the arbor shaft. The pulleys are preferably of the multigrooved type to accommodate a plurality of drive belts 32 that operate in the grooves of the respective pulleys and through a slot 33 in the floor plate 9. The pulley 30 and belts are preferably enclosed by a suitable guard 34 that is carried on the floor plate.

In order to pivot the frame and to stabilize the movement of the machine when cutting a groove, the rear end of the frame is carried on a dolly 35 including a transverse axle 36 preferably of longer length than the width of the frame 2, as best shown in Figs. 2, 4 and 5. Extending from the ends of the axle 36 are spindles 37 and 38 65 mounting pairs of wheels 39 and 40. Extending forwardly from the axle are spaced apart bars 41 and 42 and connecting the ends thereof is a sleeve 43 which is

sleeved upon the axle 12 intermediate the bearings 13 and 14, whereby the pairs of wheels 39 and 40 trail the traction wheels. The bars 41 and 42 are rigidly braced with respect to the sleeve 43 and axle 36 by a transverse plate 44 that is secured along the rear side of the sleeve 43 and to the inner faces of the bars 41 and 42. Cooperating with the plate 44 but on the outer sides of the bars 41 and 42 are braces 45 and 46 having their rear ends fixed to the axle 36 at points spaced outwardly from the rear ends of the bars 41 and 42 and their forward ends fixed to the outer faces of the bars immediately adjacent the ends of the sleeve 43. The braces 45 and 46 are additionally connected with the outer ends of the axle 36 by gussets 47 and 48. The sleeve 43 is preferably secured to the axle shaft by set screws 49 and 50 whereby the axle 12 turns within hubs of the traction wheels 10 and 11 when the pairs of wheels 39 and 40 roll upon uneven surfaces. The axles remain in substantially rigid parallel relation and the wheels provide a four-point support with the dolly wheels spaced widely apart to eliminate lateral sway and to maintain a stable, straightaway course for the cutting blade when the machine is in use, as later described. The dolly is connected with a rear part of the main frame by means of a manually actuated power lift, as later described, whereby the rear end of the main frame 2 may be raised and lowered to tilt the frame 2 for carrying the cutting blade 3 into and out of contact with the work.

Extending upwardly from the rear portion of the main frame is a cowl and handle assembly 51 comprising side members 52 and 53, each of which is formed of tubular stock to provide forward legs 54 having lower ends 55 welded to the main frame forwardly of the rear end member 8. The legs 54 extend upwardly and rearwardly at an angle with respect to the side members and terminate in rearwardly extending bar portions 56 to connect with rear legs 57 that have upper portions 58 extending downwardly in parallel relation with the front leg portions and that have lower portions 59 extending downwardly and forwardly at an angle to connect with the rear corners of the main frame 2. The front and rear legs are connected on their inner side faces by plates 60 and 61 which extend from the floor plate 9 upwardly to terminate short of the bar portions 56 to support a cowl 62 therebetween. The cowl 62 comprises a plate that is shaped to provide a forward skirt portion 63, a top 64 and a rear skirt portion 65 following the form of the upper ends of the side plates 60 and 61, as best shown in Figs. 3 and 4. Fixed to the inner sides of the side plates and extending through the front and rear skirt portions of the cowl are tubular guides 66 and 67 to mount handle bars 68 and 69 that slide therein in the fore and aft direction of the machine to project the rear ends when it is desired to use them. The rear ends of the handle bars are provided with suitable hand grips 70. The handle bars are adjustably secured in the guides 66 and 67 by clamp screws 66' having hand wheels 67' by which they may be easily manipulated (Figs. 1 and 13).

The side members are connected substantially midway of their height by a transverse bar 71 which cooperates with the axle 36 in connecting the power lift previously referred to. The power lift in the illustrated instance is a hydraulic jack 72 including a cylinder 73 and a ram 74 which slides in the cylinder. The ram 74 has its lower end pivotally connected with spaced apart lugs 75 (Fig. 4) extending upwardly from the axle 36 at a point substantially midway of the length thereof, the pivotal connection being made by a transverse pin 76 that extends through the spaced lugs 75 and through an intermediate lug 77 on the lower end of the ram. The cylinder 73 slides over the upper end of the ram and connects by means of a transverse pin 78 with lugs 79 projecting rearwardly from the transverse bar 71, as best shown in Figs. 3 and 4. The ram 74 is preferably protected by a boot 73'.

The jack 72 is operated in a direction to lift the rear end of the main frame by means of a manually actuated pump 80. The pump 80 includes a case 81 that is carried on brackets 82 attached to the inner side face of the side plate 60, as best shown in Figs. 3 and 4. The case 81 in addition to mounting the pump mechanism forms a reservoir for hydraulic fluid used in the jack and which is forced under pressure of the pump through a flexible duct 83 that connects the pump with the upper end of the cylinder 73, as best shown in Fig. 3. The pump is actuated by means of a handle 84 that projects rearwardly through a slot 85 in the rear portion 65 of the cowl to carry a hand grip 86 in convenient reach of the operator of the machine. Pressure created by the pump is released by means of a valve (not shown) but which is located in the case 81 and is common to such hydraulic mechanisms. The valve is operated by a shaft 87 which extends from the case through the rear portion of the cowl and carries an actuating lever 88. When the pump handle 84 is manipulated to actuate the pump, hydraulic fluid is forced under pressure through the duct 83 into the upper end of the cylinder 73 to act between the head of the cylinder and upper end of the ram, whereby a downward force is exerted on the axle 36 and an upward force is exerted on the cross member 71 to tilt the main frame on the traction wheels 10 and 11 and support the rear end of the main frame 2 on the dolly 35 while the cutting blade 3 is being operated to make a cut of a desired depth, as later described.

The machine is adapted to be operated in a forward direction by frictional contact of drive wheels 89 and 90 with treads of the traction wheels as shown in Figs. 1, 2 and 3. The drive wheels 89 and 90 are carried on a transverse shaft 91. The shaft 91 is journaled in bearings 92 and 93 that are adjustably mounted on arms 94 and 95, the arms 94 and 95 being pivotally connected between pairs of ears 96 and 97 depending from the under opposite sides of the main frame 2 substantially at points above and to the rear of the axle 12, as shown in Figs. 2 and 3. The rear ends of the arms 94 and 95 are connected by a crossbar 97 whereby both arms are moved, as a unit to bring the drive wheels into friction contact with the treads of the traction wheels, as later described. In order to adjust frictional contact of the driving wheels 89 and 90 with the traction wheels 10 and 11, the bearings 92 and 93 are adjustably mounted on the arms by means of jack screws 98 that may be threaded in openings provided in downturned ends 99 of the arms and which are connected with the bearings in which the drive shaft is journaled. It is obvious that by turning of the jack screws the bearings may be moved along the under sides of the arms to adjust pressure of the contact between the drive wheels 89 and 90 and the traction wheels 10 and 11.

Carried on a platform 9' above the floor plate of the main frame is a speed transformer 100 having a power input shaft 101 which is adapted to be operated from the power shaft of the engine through a belt 102, the belt 102 operating over a pulley 103 on the power shaft of the engine and over a pulley 104 on the power input shaft of the speed transformer. The speed transformer has a shaft 105 extending from the opposite side and connected through a coupling 106 with the power input shaft of a change speed gear unit 107 whereby the gear unit may be operated at any speed from zero to the maximum speed of the speed transformer 100 upon manipulation of the shift lever 108 of the speed transformer. The output shaft 109 of the gear unit 107 carries a sprocket 110 and operating over the sprocket and a similar sprocket 111 on the shaft 91 is a chain 112 to connect the drive shaft with the engine to move the machine in a forward direction, the chain operating through an opening 113 of the floor plate 9 and an idler sprocket 111' on the crossbar 97.

It is necessary to supply the cutting blade with streams

of water that are discharged on the respective sides of the blade, as now to be described. The cutting blade is therefore preferably enclosed on the upper side with a guard 114 having sides 115 connected by a rounding top 116. The sides and top are also shaped to provide rear extensions 117 to suspend a splash guard 118. The guard 114 is pivotally mounted on one or the other of the side members of the main frame by a bolt 119 that extends through a sleeve 120 fixed to the extension 117. The guard 114 is thus hingedly mounted so as to be swung retractively from covering relation with the cutting blade, as when changing blades. The guard 114 is supported on hooks 121 (Fig. 3) that engage the inner lower edge of the guard at a point forwardly of the arbor shaft 17. The guard is clamped in the hook by a clamp nut 122 on a stud 123 projecting upwardly from the sides of the main frame 2. Fixed to the top of the guard and extending thereacross on the respective sides of the stud 123 are spaced bars 124 that are adapted to be engaged by the nut 122. Since the guard is adapted to either side of the machine, each side has a stud 123 and a threaded opening for the bolt 119.

Mounted on the guard is a T-fitting 125 having laterally extending L's 126 which project over the sides of the guard to connect with hose 127 leading to nozzles 128 carried by the sides 115 of the guard, as shown in Figs. 1 and 2. Connected with the other branch of the T-fitting is a hose 129 that connects with a valve 130 which in turn is connected by means of a hose 131 with the pressure outlet connection 132 of a pump 133. The pump 133 has a suction connection 134 that is adapted to be connected by a hose (not shown) with a source of water supply (also not shown). The pump 133 is mounted on an extension 99 of the platform and rearwardly of the variable speed transformer 100. The pump 133 is actuated from a pulley 135 on the input shaft of the transformer and which carries a belt 136 operating over a pulley 137 on the pump shaft 138.

When the machine is to be guided by the handle bars, it is necessary to lift the dolly to clear the wheels thereof. This is effected by means of a spring 139 seated on the floor of the main frame at a point over the transverse axle 36 and which spring 139 is enclosed in a tubular housing 140 having its lower end fixed to the floor of the main frame and its upper end terminating below the top 62 of the cowl, as best shown in Figs. 4 and 8. Carried on the upper end of the spring is a collar 141 to which is connected a cable 142 that extends downwardly through the spring 139 over a guide pulley 143 to connect with a lug 144 on the rear of the transverse axle 36, as shown in Figs. 4 and 8. The length of the cable 142 is such that when the main frame is in horizontal position the spring 139 is compressed to give the action necessary to lift the dolly 35 after the fluid pressure in the hydraulic jack 72 has been released. When the jack 72 is operated to in effect lengthen the jack connection between the main frame 2 and the axle 33 of the dolly 35, the spring 139 is held down by the cable and is compressed to assist in returning the main frame 2 to horizontal position upon release of the hydraulic fluid from the cylinder 73 into the case 81.

This mechanism also performs an important function of actuating an indicator drum 145 which indicates the depth of cut made by a given diameter of cutting blade 3. The drum 145 is rotatably mounted on a transverse pin 146 which is supported below the top portion 62 of the cowl by brackets 147. The brackets 147 are suitably attached to the under side of the cowl and have depending flanges 148 to journal the ends of the pin 146. The drum 145 has a peripheral scale 149 for each diameter of blade to be used, for example, the ordinary blades employed in connection with machines of this character are 12, 14 and 18 inches, and therefore the drum has three scales 149 wherein the graduations thereof are respectively visible through window openings 150 in the

top portion 62 of the cowl. The indicator drum 145 is operated in one direction by a cable 151 having one end attached to the collar 141 and the other end is wrapped around the drum within a groove 152 and is anchored in a side of the groove in such a manner that when the main frame 2 is pivoted to bring the cutting blade 3 in contact with the work, the movement thereof from the normal position results in the collar 141 pulling on the cable 151 to rotate the drum a distance corresponding with the depth of cut of the cutting blade 3, consequently the graduation appearing in the proper window visibly indicates the depth of the cut. During rotation of the indicator drum to indicate position, a spring 154 is loaded to return the drum to zero position at the time the frame is returned to a position that results in lifting of the blade from the cut. The spring 154 is connected with a clip 155 that is carried on one side of the tubular housing 149, as shown in Figs. 4 and 8. The other end of the spring 154 is connected by a cable 156 that operates in a second groove 157 in the indicator drum and which is anchored thereto so that when the rear of the platform is lowered to lift the cutting blade out of the cut, the spring 139 expands, tending to make slack the cable 151, but the slack is immediately taken up by contraction of the spring 154 to furnish the action necessary to rotate the indicator drum to zero position.

Forward travel of the machine is effected by contacting the drive wheels 89 and 90 with the traction wheels 10 and 11, and the motion of the machine is stopped by lifting of the drive wheels 89 and 90 from contact with the traction wheels 10 and 11. This is effected by means of a hand lever 158 located on the outer side of the side member 53. The lever 158 is pivotally mounted on a screw 159 that is carried by a bracket 160 fixed to the forward leg 54 of the side member 53. Reciprocably mounted in a bearing portion 161 of the bracket 160 is a rod 162 having one end 163 connected with the lever 158 by links 164. The other end 163' of the rod 162 is connected by means of a turnbuckle 165 with a clevis 166 which is pivotally connected by a pin 167 to an arm 168 of a rock shaft 169. The rock shaft 169 extends transversely of the machine and has its ends journaled in bearings 170 and 171 that are carried by the forward legs 54 of the side members 52 and 53. Projecting forwardly from the rock shaft is an arm 172 which is pivotally connected by means of a link 173 with an arm 174 on the bar 97. Thus by lifting on the lever 158 the shaft 169 is rocked in a counterclockwise direction to lower the drive wheels 89 and 90 into driving contact with the treads of the traction wheels 10 and 11 to effect forward movement of the machine. When the lever 158 is moved in the opposite or clockwise direction (Fig. 1), the shaft 169 is rocked in the opposite direction to lift the drive wheels from contact with the treads of the traction wheels to stop forward movement of the machine under power of the engine 4.

The shift lever 108 for the speed transformer 100 is actuated by a lever 175 also pivotally mounted on a part 176 carried by the bracket 160. Fixed to an extension 60 of the part 176 by fastening devices such as screws 178 is a guide 179 for a cable 180. The cable 180 is slideably contained in a sheath 181, so that it may be moved longitudinally therein to transmit motion of the lever 175 to the shift lever 108, the ends of the cable being suitably connected to the respective levers. When the lever 175 is moved in a counterclockwise direction, the shift lever of the speed transformer is moved to zero position, and when the lever 175 is moved in a clockwise direction, Fig. 11, the shift lever 108 of the speed transformer 100 is shifted to increase the speed of the output shaft. In order that the maximum speed to be effected by the lever 175 may be set automatically, the lever 175 has a lug 182 that connects with a rod 183 which is slideable in an opening 184 in an ear 185 that projects from the plate 61. The rod 183 is threaded as indicated at 186 and

carries stop and jam nuts 187 and 188 so that when the lever 175 is in position for the desired speed, the stop nut 187 may be adjusted on the rod to engage the rear side of the ear 185, as shown in Fig. 10, and the stop nut 187 is locked by turning the jam nut 188 thereagainst. With this arrangement, the lever 175 may be shifted from the maximum speed desired to neutral speed and back to the desired speed without adjusting the position thereof, it being only necessary to shift the lever to the position where it is stopped by engagement of the nut 187 with the ear 185. With the controls thus far described, the levers 158 and 175 may be operated independently of each other, and therefore the speed change lever 175 may be in position where the shift lever 108 on the speed transformer 100 is not in zero position. Therefore, when the lever 158 is operated to bring the drive wheels 89 and 90 into contact with the treads of the traction wheels 10 and 11, an excessive shock is applied to the power units 100 and 107, with the result that one or both power units may be severely damaged. To avoid this difficulty, the lever 158 has an arm 188 thereon that has a laterally extending lug 189 adapted to engage a laterally extending lug 190 on the lever 175. Therefore, when the lever 158 is moved all the way down, Fig. 11, the lug 189 thereon engages the lug 190 on the lever 175 to automatically move the lever 175 of the speed transformer to neutral position. Therefore, when the lever 158 is raised to reengage the power drive of the traction wheels, the lever 175 remains in neutral position and it is impossible to start movement of the machine without subsequent movement of the lever 175 from neutral position.

A fuel tank 191 for supplying fuel to the engine is mounted on the front end of the main frame 2, and a battery 192 for supplying electric current for starting the engine and to supply the ignition system is carried at the rear end of the frame.

The machine is provided with front and rear pointers 193 and 194 that are aligned with the blade to locate the line of travel of the machine. The front pointer 193 constitutes the downturned terminal of a traverse rod 195. The rod 195 is adjustable within a sleeve 196 that is carried by a wheel 197. The wheel 197 is carried at a sufficient distance forwardly of the machine so that the pointer is in sight of the operator, as later described. This is accomplished by forwardly converging arms 198 and 199 that extend from bearing sleeves 200 and 201, the bearing sleeves being journaled between spaced pairs of lugs 202 and 203, with fastening devices 202' and 203' extending through the lugs and sleeve, as best shown in Fig. 2. As above stated, the rod 195 is adjusted in the sleeve by nuts 204 that are threaded on the rod and engage the ends of the sleeve 196. When the cutting blade is to be used on the left hand side of the machine, the rod 195 may be removed and reinstalled at the opposite side. The rear pointers 194 comprise shorter rods 205 that are adjustably mounted in lugs 206 and 207 projecting rearwardly from the axle 36. The pointed terminals 208 of the pointers are retained in desired position by nuts 209 that are threaded on the rods and engage the respective ends of the lugs, as best shown in Fig. 4. The control levers and mechanism associated therewith are preferably protected by a guard 210, as shown in Figs. 2 and 4.

In operating a machine constructed and assembled as described, the handle bars 68 and 69 when lifted upward tilt the machine forward on traction wheels 10 and 11, in which position it can be maneuvered in the manner of a conventional wheelbarrow to permit movement of the machine into position upon the surface of a concrete slab "A" in which a linear cut "B" is to be made by the cutting blade 3. The spring 139 is then effective to suspend the dolly from the frame 2 with the stabilizing wheels 39 and 40 out of contact with the surface on which the traction wheels are supported.

When the machine is in position, the wheel 197 carrying the front pointer 193 is lowered from the position shown

in Fig. 3 to the position shown in Fig. 2. The front and rear pointers 193 and 194 are then adjusted laterally relatively to markings on the surface to be followed in making the cut. Attention is particularly directed to the fact that when the machine is being maneuvered into position on the traction wheels, there is a preferably slight preponderance of the weight at the rear of the machine so that the forward end of the machine carries the blade out of contact with the surface on which the machine is maneuvered. After starting of the motor 4 the cutting blade is in motion through the driving connection which includes the pulleys 30-31 and the driving belt 32. The suction connection 136 of the water pump 133 is connected by means of a hose with a suitable source of water supply for supplying water to the cutting blade when the pump is in operation and the valve 139 is open. The pump 80 is then actuated by moving the lever 84 up and down in the slot 85 to pump hydraulic fluid from the case 81 and discharge it under pressure into the cylinder 73 through the hose connection 83. The hydraulic fluid upon entering the cylinder of the pump acts between the ram and the upper head of the cylinder to bring the stabilizing wheels 39 and 40 of the dolly 35 into bearing contact with the surface of the slab "A" and to tilt the frame 2 on the axis of the traction wheels 10 and 11 so as to bring the blade 3 into cutting contact. The control lever 158 is then raised to lower the driving wheels 89 and 90 into contact with the treads of the traction wheels 10 and 11. The stop and jam nuts 187 and 188 are adjusted on the rod 186, so that when the speed control lever 175 is moved to bring the stop nut 187 into contact with the ear 185, the lever 108 of the speed transformer 100 is shifted to the position which gives the desired speed of the driving wheels 89 and 90.

Tilting of the frame 2 compresses the spring 139 since the collar 141 holds the upper end of the spring relatively to the transverse axle 36 of the dolly 35 because of the connection of the cable 142. Tilting of the frame results in lifting the lower end of the spring, so that there is a relative movement between the frame 2 and the collar 141. Therefore, since the depth indicator drum is also carried by the frame 2 and the cable 151 is secured to the collar 141, the drum is rotated from its zero position to indicate the depth of cut through the window opening 150 that corresponds with the diameter of blade being used. The cut is brought to the proper depth by further manipulation of the pump lever 84 as the blade 3 penetrates the surface of the concrete.

In case the blade should strike a hard spot, or the operator should desire to raise the blade slightly in the cut, the operator releases the pressure from the jack by manipulating the lever 88 to bleed hydraulic fluid from the jack cylinder, responsive to the preponderance of weight on the rear portion of the frame. The movement of the frame quickly forces the hydraulic fluid from the cylinder back into the case 81.

The blade may be returned to the cut to continue the cut under the proper pressure depending upon the extent to which the operator manipulates the pump lever and the release of the fluid pressure from the jack. This is an important feature of the invention, as it provides for precision pressure feed of the blade into the cut and permits a rapid release of the blade upon release of the pressure, to protect and prolong the life of the blade.

When the blade is withdrawn from the cut, the lever 158 is actuated to effect lift of the driving wheels 39 and 40 out of contact with the tread of the traction wheels. Movement of the lever 158 also brings the lug 189 into contact with the lug 190 on the lever 175 to automatically actuate the lever 175 to move the lever 108 of the speed transformer to zero speed position. Therefore when the lever 158 is again actuated to bring the drive wheels into contact with the traction wheels, the lever 175 remains in neutral speed position so that contact of the drive wheels with the treads of the traction wheels does

not exert objectionable reaction forces upon the speed transformer or other driving connections. After contact of the driving wheels has been established, the lever 175 may then be swung forwardly until the stop nut 187 engages the ear 185, whereupon the lever 108 is returned to its original position for maintaining the desired forward speed of the machine. It is thus obvious that after the desired speed has been determined, that speed is automatically established whenever the lever 175 reaches the position where the stop nut engages the ear 185. If it becomes necessary to change the setting of the lever 175, the stop and jam nuts 187 and 188 may be readjusted on the rod 183 to give the proper forward speed of the machine.

Attention is directed to relatively wider spacing of the stabilizing wheels to give the leverage necessary to prevent the cutting blade from veering the machine off course. The double stabilizing wheels are also important to give the desired contact with the slab on which the machine is used.

When the cut is completed, the lever 88 is actuated to release the hydraulic fluid from the cylinder of the jack and the preponderance of weight on the rear of the frame produces a downward movement of the cylinder to force the fluid from the cylinder into the case 81. This movement allows the frame to return to a position where the blade is lifted from the cut.

If desired, the machine may be manually maneuvered by the operator, or the machine may be moved under power by actuating the control levers 158 and 175, whereupon the machine is propelled under power of the engine while it is being maneuvered and steered into position for making the subsequent cut.

If there is any tendency of the machine to veer from a straightaway linear path, this tendency may be eliminated by adjusting relative contact pressures of the driving wheels 89 and 90 with the treads of the traction wheels. This is readily effected by adjusting the relative positions of the bearings 92 and 93 on the arms 94 and 95, the adjustment being made by manipulating the jack screws 98 in the proper direction. The amount of pressure on the drive wheels is adjusted by adjusting the length of the rod 173.

If desired, the cutting blade and guard may be removed from the right hand side of the machine and applied to the left hand side.

From the foregoing it is obvious that I have provided a machine which is well adapted for cutting grooves in concrete slabs and which is constructed to prolong the life of the cutting blade.

What I claim and desire to secure by Letters Patent is:

1. A mobile machine for making a linear cut into the surface of a concrete slab or like structure, said machine including a main frame having a fore portion and a rear portion, a rotary cutter having fixed rotational support on the fore portion of the frame on a transverse axis, a pair of transversely aligned traction wheels having connection with opposite sides of the frame and intermediate said portions for maneuverably supporting the machine on said surface in which the cut is to be made, a dolly having transversely spaced apart stabilizing wheels adapted for rolling contact with said surface, means pivotally connecting the dolly with the frame for retaining the axis of the dolly wheels in parallel relation with the axes of the traction wheels and the rotary cutter and to cooperate with said traction wheels in maintaining movement of the machine in a linear direction, a pulley on the rear portion of the main frame and above the dolly, a cable running over the pulley and having one end connected with the dolly, a spring yieldingly connecting the other end with a part on the main frame, a coil spring having one end seating on the main frame and the other end connected with the cable for supporting the dolly with the wheels free of the slab when the main frame is in a position with the rotary cutter out of contact with

the slab whereby the dolly wheels do not interfere with maneuvering of the machine on the traction wheels, a jack connecting the dolly with the rear portion of the main frame including piston and cylinder members, and means for supplying a pressure medium to the cylinder for urging the wheels of the dolly into rolling contact with the slab to cooperate with the traction wheels in maintaining said straightaway direction on movement of the machine and to effect pivotal movement of the main frame to bring said rotary cutter into cutting contact with the slab.

2. A mobile machine for making a linear cut into the surface of a concrete slab or like structure, said machine including a main frame having a fore part and a rear part, brackets depending from opposite sides of the frame intermediately of said parts, a transverse axle carried by said brackets, main wheels rotatable on ends of the axle for maneuvering the machine on the slab and providing a pivotal axis on which the frame is adapted to rock, a cutting blade rotatably mounted on the forward part of the frame, a dolly frame having a transverse axle portion and a forward parallel sleeve portion sleeved over the transverse axle with ends thereof in contact with the brackets for retaining the axial portion of the dolly in parallel relation and from lateral movement with respect to said transverse axle, wheels carried on outer ends of the axial portion of the dolly for rotation on an axis parallel with the rotational axis of the main wheels and adapted for rolling contact on the slab to cooperate with the main wheels in holding a straightaway direction on movement of the machine, a pulley on the main frame above the dolly frame, a cable running over the pulley and having one end connected with the dolly frame, a spring yieldingly connecting the other end of the cable with the main frame, a coil spring seated on a fixed part of the main frame and having its opposite end seating against a collar on the cable for supporting the dolly frame with the wheels thereon free of the slab when the main frame is in a position supporting the cutting blade out of contact with the slab whereby the dolly wheels do not interfere with maneuvering of the machine on the main wheels, and a jack including piston and cylinder members interconnecting the dolly frame with the main frame, means for supplying a pressure medium to the cylinder member for urging the wheels of the dolly into rolling contact with the slab to cooperate with the main wheels in maintaining said straightaway direction on movement of the machine and to effect pivotal movement of the main frame to bring said cutting blade into cutting contact with the slab.

3. A mobile machine for making a linear cut into the surface of a concrete slab or like structure, said machine including a main frame having a fore part and a rear part, brackets depending from opposite sides of the frame intermediately of said parts, a transverse axle carried by said brackets, main wheels rotatable on ends of the axle for maneuvering the machine on the slab and providing a pivotal axis on which the frame is adapted to rock, a cutting blade rotatably mounted on the fore part of the frame, said rear part of the frame having a greater weight thereon to hold the main frame normally with the cutting blade out of contact with the slab, a dolly frame having a transverse axle portion and a forward parallel sleeve portion sleeved on said transverse axle with ends thereof in contact with the brackets for retaining the axial portion of the dolly in parallel relation and from lateral movement with respect to said transverse axle, wheels carried on outer ends of the axial portion of the dolly for rotation on an axis parallel with the rotational axis of the main wheels and adapted for rolling contact on the slab to cooperate with the main wheels in holding a straightaway direction on movement of the machine, a pulley on the main frame above the dolly frame, a cable running over the pulley and having one end connected with the dolly frame, a spring yieldingly con-

necting the other end of the cable with the main frame, a coil spring seated on a fixed part of the main frame and having its opposite end seating against a collar on the cable for supporting the dolly frame with the wheels thereon free of the slab when the main frame is in a position supporting the cutting blade out of contact with the slab whereby the dolly wheels do not interfere with maneuvering of the machine on the main wheels, and a jack including piston and cylinder members interconnecting the dolly frame with the main frame, means for supplying a pressure medium to the cylinder member for urging the wheels of the dolly into rolling contact with the slab to cooperate with the main wheels in maintaining said straightaway direction on movement of the machine and to effect forward pivotal movement of the main frame on the axis of the main wheels to bring said cutting blade into cutting contact with the slab, and means connected with the pulley for indicating control of the pressure medium supply means to maintain a given depth of cut.

4. In a mobile machine for making a linear cut into the surface of a concrete slab or like structure, the combination of a frame, a rotary cutter having fixed rotational support on a fore part of the frame, transversely aligned traction wheels, brackets depending from a mid-portion of sides of the frame, axle means carried by the brackets for journaling the traction wheels for maneuverably supporting the frame on said surface in which the cut is to be made and to provide a pivotal axis on which the frame is adapted to rock, a dolly pivotally connected with said axle means and trailing therefrom under a rear part of said frame and having transversely aligned stabilizing wheels, yieldable means connecting the dolly with the frame for suspending the dolly with the stabilizing wheels out of contact with said surface when the machine is maneuvered on said traction wheels, and power means connected with the dolly and a rear part of the frame for bringing the stabilizing wheels into stabilizing contact with said surface and for rocking the frame on its pivotal axis, whereby the frame acts as a lever with the cutter at one end with the power being applied between the other end and the dolly to bring the rotary cutter into cutting contact with the slab while the stabilizing wheels are bearing upon said surface to cooperate with the traction wheels in maintaining a straightaway course for the cutter.

5. In a mobile machine for making a linear cut into the surface of a concrete slab or like structure, the combination of a frame, a rotary cutter having fixed rotational support on a fore part of the frame, transversely aligned traction wheels, brackets depending from a mid-portion of sides of the frame, axle means carried by the brackets for journaling the traction wheels for maneuverably supporting the frame on said surface in which the cut is to be made and to provide a pivotal axis on which the frame is adapted to rock, a dolly pivotally connected with said axle means and trailing therefrom under a rear part of said frame and having transversely aligned stabilizing wheels, yieldable means connecting the dolly with the frame for suspending the dolly with the stabilizing wheels out of contact with said surface when the machine is maneuvered on said traction wheels, a fluid pressure actuated jack having a piston member reciprocable in a cylinder member, means for connecting one of the members with the dolly and the other with a fixed part on the rear of the frame, means on the frame for supplying fluid medium under pressure to the cylinder to actuate

the jack to urge the stabilizing wheels of the dolly into contact with said surface and for rocking the frame on said pivotal axis whereby said frame constitutes a lever with the cutter at one end with the power of said jack applied between the other end and the dolly for urging the cutter into cutting contact by the power of the jack while the stabilizing wheels are cooperating with the traction wheels in maintaining a straightaway course for the cutter, and means for releasing the fluid medium from the cylinder of the jack for returning the frame to said maneuvering position to render the yieldable means effective in lifting the dolly.

6. In a mobile machine for making a linear cut into the surface of a concrete slab or like structure, the combination of a frame, a rotary cutter having fixed rotational support on a fore part of the frame, transversely aligned traction wheels, brackets depending from a mid-portion of sides of the frame, axle means carried by the brackets for journaling the traction wheels for maneuverably supporting the frame on said surface in which the cut is to be made and to provide a pivotal axis on which the frame is adapted to rock, a dolly pivotally connected with said axle means and trailing therefrom under a rear part of said frame and having transversely aligned stabilizing wheels, a coil spring having one end seated upon a rear part of said frame, a collar at the other end of the spring, a cable connecting the collar with said dolly for resiliently suspending the dolly from the frame to support the stabilizing wheels out of contact with said frame when the frame is to be maneuvered on said traction wheels, a fluid pressure actuated jack having a piston member reciprocable in a cylinder member, means for connecting one of the members with the dolly and the other with a fixed part on the rear of the frame, means on the frame for supplying fluid medium under pressure to the cylinder to actuate the jack to urge the stabilizing wheels of the dolly into contact with said surface and for rocking the frame on said pivotal axis whereby said frame constitutes a lever with the cutter at one end with the power of said jack applied between the other end and the dolly for urging the cutter into cutting contact by the power of the jack, while the stabilizing wheels are cooperating with the traction wheels in maintaining a straightaway course for the cutter, and means for releasing the fluid medium from the cylinder of the jack for returning the frame to said maneuvering position to render the coil spring effective in lifting the dolly.
